Harold E. Nock, Newburyport, Mass., assignor to
Towle Manufacturing Company, Newburyport,
Mass., a corporation of Massachusetts

Application March 10, 1934, Serial No. 50,999

Term of patent 14 years

To all whom it may concern:

Be it known that I, HAROLD E. NOCK, a citizen of the United States residing at Newburyport, in the county of Essex and Commonwealth of Massachusetts, have invented a new, original, and ornamental Design for a Spoon or Article of Analogous Nature, of which the following is a specification, reference being had to the accompanying drawing, forming a part thereof.

In the accompanying drawing, Figure 1 is a view of one face of a spoon showing my new design; and Figs. 2 and 3 are sectional views taken at the lines 2—2 and 3—3, respectively, of Fig. 1.

The design is delineated as embodied in the handle of a spoon but it is contemplated that the design may also be embodied in or applied to the handles of forks, knives, servers and other analogous pieces of flatware which may form a part of a table service of uniform pattern.

I claim:

The ornamental design for a spoon or article of analogous nature, substantially as shown and described.

HAROLD E. NOCK.
